US00D874087S

(12) **United States Design Patent** (10) Patent No.: **US D874,087 S**
(45) Date of Patent: ** Feb. 4, 2020

(54) **CONFECTION**

(71) Applicant: **INTERCONTINENTAL GREAT BRANDS LLC**, East Hanover, NJ (US)

(72) Inventors: **Francis Amoako-Poku**, Whippany, NJ (US); **Susan Pettigrew**, Whippany, NJ (US); **Doris Tancredi**, Whippany, NJ (US); **Zi Yang**, Whippany, NJ (US); **Kishor Kabse**, Whippany, NJ (US); **Atsushi Ueminami**, Kanagawa (JP)

(73) Assignee: **INTERCONTINENTAL GREAT BRANDS LLC**, East Hanover, NJ (US)

(**) Term: **15 Years**

(21) Appl. No.: **29/677,940**

(22) Filed: **Jan. 24, 2019**

Related U.S. Application Data

(60) Division of application No. 29/642,056, filed on Mar. 27, 2018, now Pat. No. Des. 843,681, which is a division of application No. 29/607,889, filed on Jun. 16, 2017, now Pat. No. Des. 822,333, which is a division of application No. 29/557,231, filed on Mar. 7, 2016, now Pat. No. Des. 796,775, which is a continuation-in-part of application No. 29/538,880, filed on Sep. 9, 2015, now abandoned.

(57) **CLAIM**

We claim, the ornamental design for a confection, as shown and described.

DESCRIPTION

FIG. 1 is a perspective view of a confection, showing our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

1 Claim, 4 Drawing Sheets
